UNITED STATES PATENT OFFICE

2,267,274

GAS FILLING APPARATUS FOR LAMP
MANUFACTURERoland M. Gardner, Swampscott, Mass., assignor
to Hygrade Sylvania Corporation, a corpora-
tion of Massachusetts

Application May 18, 1940, Serial No. 335,979

3 Claims. (Cl. 176—2)

This invention relates to an exhausting machine for electric gaseous discharge lamps, and more particularly to a device for controlling the pressure of the gases used in the exhausting process.

An object of the invention is to provide a means for securing a correct pressure of gas in the lamp when it is ready to be sealed-off, after having been exhausted.

Another object is to provide a means for constantly securing an exact pressure of gas in the lamp after it has been exhausted.

The regulation of the pressure by a petcock or some similar device controlled by hand has proven to be undesirable because many times inaccuracies creep in due to the human element involved. In my invention the pressure is mechanically controlled.

Other objects and advantages of the present invention will be apparent from the drawing and description thereof in which:

Figure 1 is a view of the gauge, showing its relationship to those parts of the exhausting machine with which it is connected.

Figure 2 is a cross-section view of the two positions on the machine which pertain to my invention.

In my invention, when the lamp has been sufficiently exhausted and is ready to be filled with gas, it is filled to some pressure greater than the desired pressure. The excess is then pumped off through the gauge described below, and the lamp is sealed off containing gas under the desired pressure.

In Figure 1, the gauge consists of two envelopes, 1 and 2, of different diameters, one inside the other. In my invention, these envelopes are made of glass, but they may be made of metal or some other substance. On the side of the inner envelope, at a position relatively close to the bottom, there are one or more small vents, 3, inserted therein. In the bottom of the outer or larger envelope, there is a quantity of a liquid with an extremely low vapor pressure, for example n-butyl-phthalate 4. The height of this liquid, with an extremely low vapor pressure is determined by a consideration of two factors; one is the position, in respect to height, at which the small vent or vents, 3, appear on the side of the inner envelope, and the other is the amount of pressure which is desired in the lamp.

Figure 2 is a cross-section view of the two heads 23 on the exhausting machine which must be considered in a description of my invention. This view shows the two metal plates, 17 and 18, the

connecting lines 13 and 14 and the lamps 15 and 16. Plate 17 is stationary but plate 18 moves with the indexing of the machine.

In a rotary exhausting machine, such for example as the one shown in U. S. Patent 2,145,830, issued January 31, 1939, to G. A. Espersen, when a lamp has been flushed and exhausted, the machine indexes to a position where the lamp may be filled with gas. In Figure 2, this position is reached when the lamp 15 reaches a position where it establishes a connection with the line 14. This line 14 leads to a cylinder 22 or some other container in which the gas to be used is stored. If, for example, two mm. of mercury pressure is the desired pressure, between four and ten mm. may be introduced. When the lamp has been filled with gas to an excessive pressure, the machine indexes and the lamp moves to a position corresponding to the position of lamp 16 as shown in Figure 2. The pressure of gas in the lamp is maintained during the indexing movement by means of an oil seal between the plates 17 and 18.

When the lamp reaches the position assumed by lamp 16 in Figure 2, it is in contact with the line 12 leading to the gauge in my invention. This line 12 in Figure 2 is an extension of line 12 in Figure 1. When the lamp reaches this position, it contains a pressure of from 4 to 10 mm. of gas. The pressure in the line 12 at the time the lamp comes in contact with it is 2 mm. With this condition existing, the excess pressure of gas will force its way down through line 12 and into the inner envelope 1 of the gauge where it will come in contact with a height of n-butyl phthalate at the vent or vents, 3. Since 2 mm. of pressure is the desired pressure of gas to be permitted to remain in the lamp, a height of n-butyl phthalate, *h*, equivalent to 2 mm. of mercury is placed in the bottom of the outer envelope 2. Thus all pressure present in line 12, in excess of 2 mm. will bubble out through the 2 mm. of n-butyl phthalate and be drawn off by the vacuum pump 21 to which line 11 is connected.

To line 12, at a point just before the line enters the inner envelope 1 there is attached a monometer, 5, with a height of mercury, 6. To this monometer is attached two lead-in connecting wires 7, and 19 which are connected through the battery 8 and the lamp 9. This combination of a monometer and an electrical signalling device is employed as a leak detector. Thus when a lamp on the rotary exhausting machine reaches the position where it is in contact with line 12, it should have between four and ten mm. pressure

of gas. If it contains a pressure somewhat in excess of this amount, the height of mercury 6 will be depressed and the height of mercury 20 will rise under the influence of this pressure.

When the mercury column 20 reaches a height where contact is established with lead-in wire 19, the circuit becomes closed and the light 9 will glow, indicating the pressure condition to the operator, who may then open the petcock or valve 10 and allow the vacuum pump to pump out the line 12 directly through the shunt path 24 instead of through the n-butyl phthalate gauge. If this arrangement were not used, it would not be possible to evacuate line 12 in case it became filled with air caused by a leaky lamp, for there would always be at least 2 mm. of air in line 12 due to the height of n-butyl phthalate in the gauge.

What I claim is:

1. In an automatic gas-filling machine for

lamps, a device regulating the gas pressure to be sealed into the lamp, said device comprising: a quantity of liquid having a low vapor pressure; an envelope forming a reservoir for said liquid; an exhaust pump in communication with said envelope above the surface of said liquid; a tube extending into said liquid in said reservoir, said tube having at least one small vent below the surface of said liquid; a head for connection to lamps to be exhausted and filled; and means for placing said head in communication with said tube.

2. The combination of claim 1 in which the said liquid is n-butyl phthalate.

3. The combination of claim 1 and: a shunt path between the head and exhaust pump; and a valve for closing said path.

ROLAND M. GARDNER.
